UNITED STATES PATENT OFFICE.

WILLIAM F. ROBERTSON, OF CINCINNATI, OHIO.

TUFTING-WASHER.

1,111,034.

Specification of Letters Patent. Patented Sept. 22, 1914.

Application filed April 21, 1914. Serial No. 833,407.

To all whom it may concern:

Be it known that I, WILLIAM F. ROBERTSON, a citizen of the United States, residing at Cincinnati, in the county of Hamilton and State of Ohio, have invented certain new and useful Improvements in Tufting Washers, of which the following is a specification.

This invention relates to an improved fastening for the tufting or plaiting of upholstering for vehicles, furniture, &c., and for analogous purposes, said fastening comprising a tufting button having a head and a shank, and a washer having an opening for the shank of the button, said shank adapted to be passed through the upholstering and the opening in the washer and to be spread or bent to securely hold the button in place and to the washer.

The leading feature of my invention is the washer itself and which washer is specially fashioned to give it increased strength and rigidity, and, also, to protect the burlap, canvas or other back part of the upholstering by omitting from the washer any sharp angles or edges which would tend to abrade or cut the burlap, canvas or other fabric against which the washer is held under some pressure when the head and washer are united to form an operative fastening, and as I will hereinafter describe and claim.

In the accompanying drawing forming part of this specification and in which similar reference characters indicate like parts in the several views: Figure 1 is a sectional view of a fragment of tufted upholstering showing one form of my improvement applied thereto. Fig. 2 is a plan view and Fig. 3 is a sectional view of a washer detached. Figs. 4, 5, 6, 7, 8, 9 and 10 show slightly modified forms of washers.

In Fig. 1 of the accompanying drawings I have illustrated sufficient of a tufted upholstering to make one of the uses of my invention fully understood and wherein, A, designates the outer covering of some suitable or desired material, and B, is the usual backing or foundation which may be burlap, canvas, straw-board, or other suitable material.

The tufting button, C, may be of the usual or any suitable form having a head, a, covered or otherwise, and a shank, b, single or divided. For illustrative purposes I have adopted a button whose shank is split lengthwise to form two prongs, c, which are de-

signed to be inserted through the covering and backing or foundation of the upholstering, said shanks, or prongs, serving with a co-acting washer, which I will hereinafter describe, to hold the aforesaid parts of the upholstering together at the tufting points.

In the drawings I have shown several modified forms of washers which I may use with the tufting button described or with any other form of tufting button or like device, but in each of the forms of washers illustrated there is present the leading feature of my improvement, as I will now explain.

The ordinary washer used for upholstering purposes is stamped or otherwise formed from sheet metal, as tin, and is usually in the form of a flat disk pierced at its center to receive the shank of the tufting button and beneath which washer the end of the shank, or the ends of the prongs of the shank when a split or divided shank is used, is bent to thereby hold the button and shank together and with the upholstering clamped therebetween. In the washers heretofore employed for the purposes stated, the peripheral edge, when the washer is in use, lies in direct contact with the backing or foundation of the upholstering so that in a comparatively short time the canvas, burlap or other backing is injured by the sharp edge of the washer cutting into the same.

The improved washers shown in the drawings are each formed with the peripheral edge rounded or turned down or away from and out of direct contact with the burlap, canvas or other backing whereby a rounded surface, as distinguished from the sharp edge of the flat washers of the prior art is presented to the burlap, canvas or other material and there is absent any part which would tend to abrade or cut the burlap or canvas when the washer is tightly clamped thereagainst.

The washer, D, may be of any suitable size according to the character of the upholstering. It is shown as being in the form of a circular disk but manifestly it may partake of any other desired design so long as there is present therein the downturned projecting edge and a substantially extended or broad smooth bearing surface next to the burlap or canvas backing. The washer of Figs. 1 and 2, has a central opening d, which may be circular or may be of rectangular or slotted form, as shown at d' in

Fig. 5. In the preferred form of washer, shown in Figs. 1 and 2, the central portion is depressed and between this depressed portion and the peripheral edge there is formed 5 an annular corrugation, 2, which materially stiffens the washer and better adapts it for the intended work. The mere depressing of the central portion of the washer, as shown in Fig. 4, increases the stiffness and rigidity 10 of said washer, but a better result is obtained when the additional corrugation, 2, or its equivalent, is employed. The corrugation, however, need not be circular in outline; in Fig. 6 it is shown many-sided as at 3, and 15 it may be substantially radial as at 4—5 in Figs. 7 and 8, or it may partake of the form of a series of depressions as at 6 in Fig. 9. In other words, the specific character of the corrugation is immaterial, my invention 20 comprehending broadly any means for upsetting or deflecting a portion, or portions, of the washer to give added rigidity to the washer as a whole. Also, a corrugated dished washer, D^o, as shown in Fig. 10, 25 would come within the scope of my invention since the edge in this case is so displaced relatively to the backing of the upholstering that it does not contact directly therewith so as to have a tendency to cut or 30 injure the same.

In all of the forms of washers shown, the object is to stiffen the washer and to purposely turn the sharp edge of the washer to one side and away from the canvas, burlap or other back part of upholstering for buggies, carriages and automobiles, furniture, or other purposes, to thereby protect this flexible material from the edge of the washer, and also from the points of the 40 shank of the tufting button.

The shank of the button passes through the upholstering at the tufting point and also passes through the opening or slot in the washer and the end, or ends, of the 45 shank is then bent to one side, to hold the button and washer in relative position.

By turning down the peripheral edge of the washer, the fabric of the upholstering is not only protected but said downturned 50 edge forms substantially an annular housing, e, on what would be the back of the washer for the end, or ends, of the bent shank, or the prongs thereof, thereby preventing the possibility of the same injuring 55 the fabric backing of the upholstering. The construction specified enables the bent end of the shank, or the prongs in the case of a divided or split shank, to be practically contained within the housing and to be within 60 the plane of the downturned edge of the washer. If desired, the washer may be formed with an annular rib or corrugation,

f, surrounding the central opening and which materially strengthens the wall of the opening. 65

In Fig. 5, the central opening is formed by pricking the center to form the stiffening tongues or flanges, h. In this case the opening is elongated and appears more like a slot, but the opening may be circular, or 70 otherwise, as desired.

In using a button having a shank or a prong or prongs of sufficient length, when bent, to extend beyond the peripheral edge of the washer, the turned edge of said washer 75 will, it is apparent, so deflect the shank or prong that the extremity of the same will be held out of abrading or damaging contact with the backing of the upholstering.

Having thus described my invention what 80 I claim as new and desire to secure by Letters Patent is—

1. As an article of manufacture, a tufting washer having a peripheral edge turned to one side to carry it out of engagement with 85 the fabric forming the back of the upholstering, said washer being corrugated inside of said edge.

2. As an article of manufacture, a tufting washer depressed between its center and periphery to give it increased rigidity, said washer having a peripheral edge turned to one side to carry it out of engagement with the fabric forming the back of the upholstering, said washer being corrugated inside of 95 said edge and said turned edge of the washer forming an inclosing housing. 90

3. As an article of manufacture, a tufting washer depressed between its center and periphery to give it increased rigidity, said 100 washer having a peripheral edge turned to one side to carry it out of engagement with the fabric forming the back of the upholstering, and said washer having a central opening and a strengthening rib surrounding 105 said opening.

4. The combination with a tufting button having a head and shank, of a washer having an opening to admit said shank, said washer having a substantially convexed surface corrugated between the center and circumference and adapted to directly engage the backing of upholstering and having a peripheral edge turned to one side and away from the backing and adapted to form an 110 inclosing housing into which the shank of the button may be turned, substantially as and for the purposes described. 115

In testimony whereof I affix my signature in presence of two witnesses.

WILLIAM F. ROBERTSON.
